DESIGN FOR A PACK-ROPE SECURING
DEVICE

Alvin W. Anderson, Granger, Wyo.

Application July 23, 1941, Serial No. 102,396

Term of patent 14 years

To all whom it may concern:

Be it known that I, Alvin W. Anderson, a citizen of the United States, residing at Granger, in the county of Sweetwater and State of Wyoming, have invented a new, original, and ornamental Design for a Pack-Rope Securing Device, of which the following is a specification, reference being had to the accompanying drawing, forming part thereof.

Figure 1 is a front elevational view of a pack-rope securing device, showing my new design.

Figure 2 is a side elevational view thereof.

Figure 3 is an end elevational view thereof, as viewed from the top of Figure 1.

I claim:

The ornamental design for a pack-rope securing device, as shown.

ALVIN W. ANDERSON.
